UNITED STATES PATENT OFFICE.

JAY G. DINGER, CHARLES C. DINGER, AND GUSTOV C. SHAFFER, OF CHICAGO, ILLINOIS.

RAILWAY-TIE.

1,083,667.

Specification of Letters Patent.

Patented Jan. 6, 1914.

Application filed July 11, 1913. Serial No. 778,437.

To all whom it may concern:

Be it known that we, JAY G. DINGER, CHARLES C. DINGER, and GUSTOV C. SHAFFER, citizens of the United States, and residents of the city of Chicago, county of Cook, and State of Illinois, have invented certain new and useful Improvements in Railway-Ties, of which the following is a specification.

10 Our invention relates to railway ties and more particularly to hollow metallic ties.

The object of this improvement is the production of a hollow metallic tie which will have the resiliency of conventional wood ties 15 and provide a means for locking the rail to said tie.

A further object is to provide a construction of the character mentioned which will be of simple construction and efficient in 20 operation. Other objects will appear hereinafter.

The invention consists in the combinations and arrangements of parts hereinafter described and claimed.

25 The invention will be best understood by reference to the accompanying drawing forming a part of this specification, and in which—

Figure 1 is a view, in perspective, of a 30 railway tie embodying our invention, Fig. 2 is an enlarged longitudinal section of the same, Fig. 3 is an enlarged perspective view of a rail supporting plate used in the construction, Fig. 4 is an enlarged perspective 35 view of one of the rail holding flanges, and Fig. 5 is a perspective view of a wedge used in the construction.

The preferred form of construction as 40 illustrated in the drawing comprises a hollow metallic tie 6 struck up and being substantially rectangular in cross section with the exception of the central portion of its lower side. At the under side of the tie 6 is provided downwardly curved edge portions 7 which overlap each other. The 45 downwardly curved portion provides a means for better positioning the tie in a ballast of the road bed. The edges 7 are overlapped and placed loosely together in 50 order to give proper resiliency to the tie.

Cut out and struck up from the top wall 55 of the tie are integrally formed rail clamping jaws 8 formed to fit the flange and web of one side of a conventional railway rail 9. Coöoperating clamping jaws 10 are formed of separate pieces of metal and

struck up substantially as indicated with portions extending into the tie 6 through the opening made by striking up the jaws 8. The portions 11 of the cooperating jaws 10 which extend into the tie 6 are provided with downwardly curved parts 12 at their inner ends providing locking means to engage recesses 13 in the top faces of the wedge members 14. The coöperating jaws 10 are preferably made of resilient material and the portions 11 so shaped that said portions 11 will be under tension when the wedges 14 are in operative positions such as indicated in Fig. 2. A substantially 70 square shoulder 15 is formed on the upper side of each of the wedges 14 to engage the corners 16 of the coöperating jaws 10 to prevent the wedges from being driven too far into the tie during their application to the 75 tie. The toe end of the wedge is provided with a recess 17 to permit the curved parts 12 of the portions 11 to pass into proper position in driving the wedges 14 into their places.

80 The upper edges of the side walls of the tie 6 are recessed to a distance corresponding with the thickness of the plates 18 which are used to support the rails 9 on the tie. This provides a supporting plate for 85 the rails coplanar with the upper surface of the tie. The ends of plates 18 are bent downwardly to prevent displacement thereof.

The tie 6 is provided with an opening 19 through which a drift pin may be used to 90 dislocate the wedges 14 from their positions when so desired. The wedges are preferably placed in position in one end of the tie, when the tie is positioned, such as indicated in Fig. 1, the wedge is entered from 95 the left end of said tie and driven to its place under the rail near the right hand end of the tie. Then the wedge for locking the rail at the left end of the tie is placed in position at the left hand end of the tie and driven to its proper position. In removing the wedges, the wedge nearest the left hand end of the tie is dislocated by means of a drift pin operating in hole 19 in the tie. The wedge 14 at the right hand end of the tie is removed by using the drift pin at the right hand end of the tie.

100 While we have illustrated and described the preferred form of construction for carrying our invention into effect, this is capable of variation and modification without departing from the spirit of the invention.

We, therefore, do not wish to be limited to the precise details of construction set forth, but desire to avail ourselves of such variations and modifications as come within the 5 scope of the appended claims.

Having described our invention what we claim as new and desire to secure by Letters Patent is:

1. A railway tie comprising a hollow metallic body having integral rail clamping jaws struck up from the upper wall thereof; coöoperating rail clamping jaws having portions entering the hollow tie through the opening formed in striking up said integral 10 jaws and extending along the under side of the top wall of the tie; and wedges in said tie under said coöoperating jaws and having recesses in their top faces preventing retrograde movement thereof, substantially 15 as described.
2. A railway tie comprising a hollow metallic body having integral rail clamping jaws struck up from the upper wall thereof; coöoperating rail clamping jaws having portions entering the hollow tie through the opening formed in striking up said integral 20 jaws and extending along the under side of the top wall of the tie, said portions extending into said tie having downwardly curved parts in their ends; and wedges in said tie under said coöoperating jaws and

having recesses in their top faces engaging the downwardly curved parts of said coöperating jaws preventing retrograde movement thereof, substantially as described. 35

3. A railway tie comprising a hollow metallic body having integral rail clamping jaws struck up from the upper wall thereof; coöoperating rail clamping jaws having portions entering the hollow tie through the 40 opening formed in striking up said integral jaws and extending along the under side of the top wall of the tie, said portions extending into said tie having downwardly curved parts in their ends; and wedges in said tie under said coöperating jaws, having recesses in their top faces engaging the downwardly curved parts of said coöperating jaws preventing retrograde movement thereof and being provided with shoulders engaging 45 said coöperating jaws preventing said wedges from being driven too far in the tie, substantially as described. 50

In testimony whereof we have signed our names to this specification in the presence of two subscribing witnesses. 55
